UNITED STATES PATENT OFFICE.

ALBERT J. POVAH, OF SOUTH BOSTON, MASSACHUSETTS, ASSIGNOR TO UNITED SHOE MACHINERY COMPANY, OF PATERSON, NEW JERSEY, A CORPORATION OF NEW JERSEY.

CAM-CUTTING MACHINE.

1,118,442.

Specification of Letters Patent.

Patented Nov. 24, 1914.

Application filed July 31, 1906. Serial No. 328,570.

To all whom it may concern:

Be it known that I, ALBERT J. POVAH, a citizen of the United States, residing at South Boston, in the county of Suffolk and 5 State of Massachusetts, have invented certain new and useful Improvements in Cam-Cutting Machines; and I do hereby declare the following to be a full, clear, and exact description of the invention, such as will enable others skilled in the art to which it 10 pertains to make and use the same.

The present invention relates to improvements in cam-cutting machines.

In a cam mechanism operating at high 15 speed it is necessary, in order that the wear on the cam and cam roll, and the noise incident to their operation, may be reduced to a minimum, that the cam surfaces be accurately formed so that in all positions to 20 which the cam roll is moved by the joint action of the cam and the mechanism upon which the cam roll is mounted the cam path and the cam roll should accurately engage each other over the whole or a substantial 25 part of the width of their bearing surfaces, for if they engage only at a single point this point will be rapidly worn or hammered away and the operation of the mechanism will become inaccurate and noisy. It is also 30 necessary, where a cam of the closed type is used, that the cam groove in which the cam roll is moved be of a width only sufficient to permit the cam roll to pass freely there-through, for any looseness sufficient to allow 35 substantial lost motion will result in hammering of the cam roll against the cam and the rapid deterioration of the parts.

When the cam roll is mounted on a slide moving parallel to the axis of rotation of 40 the cam, or on a lever pivoted to oscillate only in a plane perpendicular to the axis of the cam, the formation of a correct cam surface or groove is comparatively simple and may be accomplished by a cam-cutting 45 machine of ordinary form, having a cutter mounted on a sliding carrier controlled by a pattern plate or leader. But where the cam roll is so mounted that its axis does not remain in the same plane as the axis of rotation 50 of the cam, as, for example, where the cam roll is carried by a lever mounted to oscillate about an axis not parallel with the axis of the cam, the form of the cam surface necessary to engage the cam roll accurately in all

positions is not such as can be generated accurately by a cam-cutting machine of the ordinary form. It has been customary, therefore, to cut such cams on an ordinary machine and then to scrape the cam surfaces in order to make them approximate more 55 nearly the correct form. This method is expensive, however, and does not result in a perfect cam, being particularly unsatisfactory in the case of a closed cam, in which the scraping of the groove at certain points 60 results in variations in the width of the groove and in consequent looseness, resulting in hammering of the cam roll when in 65 operation and lost motion in the mechanism actuated thereby.

The object of this invention is to produce a cam-cutting machine in which cams of the character above referred to may be cut in an accurate manner so as to obviate hand work or other finishing operation and the 70 resulting disadvantages.

The present invention is particularly adapted for cutting the cam by which the looper is actuated in the well-known Goodyear type of shoe-sewing machine. The 75 looper cam of the Goodyear machine is adapted to impart a compound oscillating movement to a lever mounted on a universal fulcrum which permits oscillations in all directions, and, owing to the peculiar movement of 80 this lever and the cam roll the correct cam path for actuating these parts is of an irregular form which can be only roughly approximated by an ordinary cam-cutting machine.

The invention consists in the improved 85 cam-cutting machine hereinafter described and defined in the claims.

In the drawings Figure 1 is a front elevation of an improved cam-cutting machine embodying in preferred form the present 90 invention; Fig. 2 is a right-hand end elevation; Fig. 3 is a left-hand end elevation, and Fig. 4 is a plan view.

In the illustrated embodiment of the invention, which is a machine adapted to cut 100 both peripheral and lateral cam grooves or surfaces on a circular cam blank, the blanks are mounted and rotated in substantially the same manner as in previous cam-cutting machines, but the milling cutters by which the 105 cam surfaces are formed are mounted upon and directed by pivoted levers which, in respect to their length and the point at which

they are pivoted, have the same relation to the cam blanks as the cam lever of the machine in which the cam is to be used has to the cam in said machine. The machine is, 5 for convenience, provided with two blank-supporting mandrels and two cutter-carrying levers, so that a cam having both peripheral and lateral grooves or surfaces may be cut in two operations, and so that two 10 cam blanks may be operated upon in the machine at one time.

Considering first the mechanism for cutting peripheral cam surfaces, the cam blank 1, Figs. 2 and 4, is secured to a mandrel 2 journaled in columns 3 mounted on the bed plate 4 of the machine. A rotary milling cutter 5 is fixed to a short shaft 6 journaled in one end of a lever 7. The cutter lever 7 is pivoted in a fork 8, Figs. 1 and 4, having 15 a stem 9 pivotally mounted in a standard 10 on the bed-plate of the machine, this construction forming a universal joint permitting oscillating movements of the cutter lever 7 in every direction. The milling cutter 20 5 is rotated by a flexible shaft 11 connecting the shaft 6 with a stepped driving pulley 12 actuated by belt connections with a suitable 25 source of power.

In order to guide the milling cutter 5 so 30 as to generate the proper contour on the periphery of the cam blank, a guide roll 13 is mounted on the left-hand end of the cutter lever 7, this guide roll resting upon a pattern plate or leader 14 which is mounted upon a mandrel 15 parallel to the cam-blank mandrel 2. As the milling cutter 35 operates upon the cam blank, the latter is slowly rotated to feed new portions of its surface to the milling cutter, and the leader 14 is simultaneously rotated at the same 40 speed and in the same direction to guide the milling cutter. The mandrels 2 and 15 carry at their outer ends worm wheels 16 and 17 respectively which are engaged by 45 worms 18 on a worm shaft 19. The worm shaft 19 is connected by bevel gears 20 with a sleeve 21 journaled in a lug 22 on the bed-plate of the machine and concentric with a feed shaft 23 journaled at one end in the 50 sleeve 21 and at the other end in a lug 24 on the bed plate. The sleeve 21 has formed at one end a series of clutch teeth which may be engaged by a sliding clutch member 25 splined to the feed shaft 23 and free to 55 be moved longitudinally thereon by the operator in order to connect or disconnect the worm shaft and feed shaft to start or interrupt the feed. The feed shaft 23 carries at its rear end a cone pulley 26 connected 60 by a belt 27 with a corresponding cone 28 (see Fig. 2) which is journaled on the frame of the machine. The cone pulley 28 is connected by a sprocket chain 29 with a sprocket 30 driven by the driving pulley 12. 65 By shifting the belt 27 on the cone pulleys

the rate of feed of the cam blank and leader may be varied according to the size or material of the cam blank.

The pivotal support of the cutter lever 7 is arranged midway between the ends so that 70 the movements imparted to the guide-roll 13 and the milling cutter 5 are equal in amplitude but opposite in direction, a prominence on the leader corresponding with a 75 depression in the cam. In the drawings the 80 machine is shown as operating at its right-hand portion upon an irregular cylindrical cam, and therefore a single leader is used in this part of the machine, the capacity of the cutter lever 7 for oscillating in a horizontal plane not being utilized. Accidental 85 oscillations in a horizontal direction are prevented when the machine is used in this manner, by tightening the nut 31 on the bottom of the stem 9 forming part of the 90 joint on which the cutter lever 7 is mounted.

To adapt the machine to cut cams of different widths and diameters, and cams for actuating cam levers of different lengths, horizontal adjustments are provided for the 90 columns upon which the cutter lever and the mandrels are mounted. The column 10 on which the cutter lever 7 is mounted is connected by a bolt 32 with a T-slot 33 in the base plate of the machine so that it may 95 be moved forwardly and rearwardly according to the width of the cam blank operated upon, and the columns on which the mandrels are mounted are similarly secured to the base plate by means of T-slots 34 100 which permit lateral adjustment of the mandrels for the use of cutter levers of different lengths corresponding to cam levers of different lengths. The driving pulley 12 is similarly mounted to permit lateral adjustment, though this is not always necessary, owing to the use of the flexible shaft. 105

The left-hand portion of the machine is arranged to cut peripheral cam grooves. As shown in the drawings, it is arranged to cut 110 a peripheral groove in a cam blank on which a peripheral cam surface has already been formed in the right-hand portion of the machine. The mandrels 35 and 36 upon which the cam blank and the leaders are carried 115 are substantially similar in construction and operation to those of the right-hand part of the machine, and the feeding means are identical with those of the right-hand part. The cutter lever 37 is mounted in the same 120 manner as the cutter lever 7. A milling cutter 38 is journaled in a vertical position on the lever 37 and is driven by a flexible shaft 39 connected with a shaft 40 journaled in a housing 41 on the frame of the machine. 125 The shaft 40 is connected by bevel gears 42 with a horizontal shaft 43 connected by gears 44 with a driving pulley 45 connected by a belt with a suitable source of power.

In order to keep the milling cutter 38 130

in proper engagement with the periphery of the cam blank 46 on the mandrel 35 the cutter lever 37 is provided with a guide roll 47 engaging a leader 48 on the mandrel 36, this leader being similar in form to the leader 14, so as to cause the milling cutter to follow the outline which has been previously imparted to the cam blank 46 on the right-hand part of the machine. The lateral movements of the milling cutter are controlled by a leader 49 mounted on the mandrel 36, the leader 49 being engaged by a guide roll 50 (see dotted lines in Fig. 1) carried by the cutter lever 37. The cam roll 50 is maintained in engagement with the leader 49 by means of a spring 51 connected with the cutter lever 37 and with the frame of the machine. As the cam blank 46 and the leaders 48 and 49 are rotated slowly in unison, the milling cutter, while rotating and cutting the groove in the cam blank, moves with relation to the cam blank precisely as the cam roll moves with relation to the cam in the machine in which the cam is to be used, and thus the cam groove is cut in precisely the proper form to engage the cam roll accurately in all positions.

In order to feed the milling cutter 38 into the blank at the commencement of its operation, the milling cutter is mounted on a shaft 53 (see Fig. 1) journaled in a sleeve 54 threaded into the end of the cutter lever 37. The sleeve 54 is provided with a hand wheel 55 by which it may be turned to advance the cutter longitudinally into the cam blank.

By simple re-arrangements of the parts the machine may be arranged to cut lateral cam grooves or surfaces. To cut lateral cam grooves the feeding device comprising the shaft 53 and threaded sleeve 54 may be mounted in the right-handed end of the cutter lever 7, while the left-hand portion of the machine may be arranged to cut a lateral cam surface by mere adjustment of the positions of the parts.

By using milling cutters of the same diameter and cutter-carrying levers of the same length as the cam roll and cam lever in the machine in which the cam is to be used, and by mounting the cutter-carrying lever on a pivotal support having the same relation to the cam blank that the support of the cam lever in the said machine has with respect to the cam, a cam may be cut having a surface which will accurately engage the cam roll throughout its operation, the cam requiring no scraping or other work to finish it. Where the machine is used to cut a cam with a groove, the groove is of exactly the proper width throughout, so that there is no lost motion between the cam roll and the cam.

65 The invention is not limited to the de-

tails of construction and operation of the illustrated embodiment nor to the conjoint use of all its features, but may be embodied in other forms within the terms and spirit of the claims.

Having now described the invention, what is claimed is:

1. A cam-cutting machine for cutting cams adapted to impart compound oscillations to a lever, having, in combination, 75 means for supporting and rotating a cam blank, a cutter-carrying lever of substantially the length of the lever to be actuated by the cam, mounted on a universal joint to permit compound oscillation, means acting 80 automatically to direct the oscillations of the lever, a rotary cutter journaled on the said lever and held in contact with the blank, and means for rotating the cutter, substantially as described.

2. A cam-cutting machine, having, in combination, means for supporting and rotating a cam blank, a cutter-carrying lever mounted between its ends on a universal joint, a rotary cutter journaled on one end 90 of the lever and held in contact with the blank, leaders engaging the other end of the lever and acting to impart oscillations in two planes to the lever, and means for actuating the leaders, substantially as de- 95 scribed.

3. A cam cutting machine, having, in combination, means for supporting and rotating a cam blank continuously in one direction, a cutter carrier pivotally mounted to permit oscillations in two planes, a cutter carried by the cutter carrier and held in engagement with the cam blank, and means for automatically oscillating the cutter carrier in said two planes as the blank is ro- 100 105 tated, substantially as described.

4. A cam cutting machine, having, in combination, means for supporting a cam blank, means under the control of the operator for rotating the blank, a rotary cutter, a cutter 110 carrier, means for positively rotating the cutter, manually operated means for moving the cutter in the direction of its length into the work, and means for automatically moving the cutter carrier in two planes as 115 the blank is rotated, substantially as de- scribed.

5. A cam cutting machine, having, in combination, means for supporting and rotating a cam blank, a cutter carrying lever, a ro- 120 tary cutter supported thereby and held in contact with the blank, pattern cams operatively connected to the lever and arranged to impart automatically oscillations in two planes to the cutter, and means for actuating the pattern cams, substantially as de- 125 scribed.

6. A cam cutting machine, having, in combination, a supporting shaft for a cam blank, a pattern cam, a supporting shaft for the 130

pattern cam parallel to the first mentioned shaft, a cutter carrier lever extending transversely of the shafts and adapted to be moved automatically by the pattern cam in 5 two planes, and a cutter carried upon one end of the lever and held in engagement with the cam blank, substantially as described.

7. A cam cutting machine, having, in combination, a supporting shaft for a cam blank, a supporting shaft for a pattern cam parallel thereto, means for simultaneously rotating the shafts, a cutter carrying lever, a cutter mounted on one end of the lever in operative relation to the cam blank, and a pattern cam operatively connected to the opposite end of the lever to impart automatically a universal movement to the lever and actuate the cutter in a path corresponding to the 20 contour of the pattern cam, substantially as described.

8. A cam cutting machine having, in combination, means for supporting and rotating a cam blank, a cutter carrier mounted to oscillate in two planes, a cutter journaled on the carrier and held in engagement with the cam blank, means for automatically oscillating the cutter carrier in said two planes 25 and means for positively rotating the cutter, 30 substantially as described.

9. A cam-cutting machine, having, in combination, means for supporting and rotating a cam blank, a cutter carrier, a cutter journaled on the carrier and held in engagement with the cam blank, means for rotating the cutter, and means for imparting automatically relative oscillating movements in two planes to the cam blank and cutter carrier, 35 substantially as described.

10. A cam-cutting machine for cutting cams adapted to impart compound oscillations to a lever, having, in combination, means for supporting and rotating a cam blank, a cutter-carrier, a rotary cutter journaled on said carrier and held in contact with the blank, means for rotating the cutter, and means for imparting automatically relative oscillating movements to the cam blank and cutter carrier in two planes about a center located at a distance from the cutter 40 substantially equal to the length of the lever to be actuated by the cam, substantially as described.

In testimony whereof I affix my signature, in presence of two witnesses.

ALBERT J. POVAH.
